UNITED STATES PATENT OFFICE.

JOHN F. LAWSON, OF OSHAWA, ONTARIO, CANADA.

ROTARY PUNCH AND PRESS.

1,171,794.

Specification of Letters Patent. Patented Feb. 15, 1916.

Application filed November 27, 1915. Serial No. 63,894.

To all whom it may concern:

Be it known that I, JOHN F. LAWSON, of the town of Oshawa, in the county of Ontario, Province of Ontario, Canada, have invented certain new and useful Improvements in Rotary Punches and Presses, of which the following is a specification.

This invention relates to apparatus for punching, pressing or cutting sheet material, and my object is to devise rotary means for acting on the material as it travels whereby the time, and therefore the cost of production, is materially decreased.

I attain my object by journaling a plurality of die-beds on each of two pairs of rotary disks, the die-beds of one pair of disks being adapted to coöperate with the die-beds of the other pair of disks. The die beds are controlled by cams, so that when two opposed die beds approach a coöperative position they are approximately parallel. As the two are brought closer together by the rotation of their supporting disks, their parallelism is accurately maintained by means of telescoping parts rigidly secured to said die-beds of their journals. Means are provided for adjusting the relative position of the two pairs of disks with their die beds and for feeding the work between the die beds.

The whole is constructed as hereinafter more specifically described and as illustrated in the accompanying drawings in which—

Figure 1 is a side elevation of the machine; Fig. 2 is a side elevation partly in section; and Fig. 3 an end elevation.

In the drawings like numerals of reference indicate corresponding parts in the different figures.

1 is the frame of the apparatus suitably shaped to support the different parts. On this frame are carried two rotary supports on which die beds are journaled. Each support preferably comprises a pair of disks 2 connected by a shaft 3. The shaft for the lower support is journaled in any suitable manner on the frame of the apparatus. The shaft 3 of the upper support is journaled in boxes 4 vertically movable in the guides 5 formed in the frame of the machine. Each box is vertically adjustable by means of a screw 6 threaded through the nut 7 secured to the top of the frame. The screws 6 must be so connected to the boxes that the screws will rotate freely and will be held from longitudinal movement rela-

tive to the boxes, and thus the boxes may be held in any suitable vertical position to adjust the die bed supports relative to one another.

The die beds 8 are journaled in the disks so that the die beds may be moved to maintain a substantially parallel position when in coöperative relationship. The die beds are actuated by means of the cams 9, which are provided with suitable cam grooves with which crank arms 10 connected to the journals of the die beds are adapted to engage. These cams bring coöperative die beds into substantial parallelism as they approach one another, and this parallelism is accurately maintained by telescopic means connected with the die beds themselves. For this purpose I provide the die beds at one or both ends with telescopic means comprising the tube 11 connected to the journal of one of the die beds and a pin 12 connected to the journal of the opposed or coöperating die bed. The pin enters the tube and thus the beds are held accurately in parallelism while they are free to approach and retreat from one another as the supporting means rotate. The die beds may carry punches, forming dies, shears or the like. From this construction it is evident that the work may be operated on while traveling through the machine, thus effecting a great saving in time. The pressure of the dies may be accurately regulated by means of the screws 6.

The die bed supports may be actuated in synchronism by any suitable means. I show the shaft 3 of each support provided with a worm wheel 13 with which mesh the worms 14 on the vertical shaft 15. This shaft is actuated by means of bevel gearing 16 from the main shaft 17, which may be actuated in any suitable manner. The driving gear may be duplicated at the opposite side of the machine if necessary.

I provide an automatic feed for the work arranged in the manner I will now describe. Pairs of feed rolls 18 are provided both in front of and behind the die bed supports. These feed rolls are constructed and arranged in the ordinary manner and are actuated by the gearing 19 through the medium of which the rolls of each pair operate simultaneously. With the lower gear 19 of each pair meshes a gear wheel 20. These gear wheels 20 are secured to spindles 21 suitably journaled on the frame of the machine and carry the sprocket wheels 22, on

which are carried the sprocket chain 23, which serves as a medium for actuating the feed rolls. This sprocket chain is intermittently actuated by means of the pins 24 carried by the lower die beds 8. These pins engage through the links of the chain as shown so that the feed is continuous as long as the die beds are in coöperative position. The extent of the feed can be readily regulated by varying the extent of the projection of the pins from the die beds. This adjustment is readily effected by having the pins slideable in suitable holes in the die beds and clamping them in position by means of 15 the set screws 25.

It should be stated that the lower cam 9 is preferably secured to the frame of the machine, while the upper cam 9, as it must be vertically movable with the support of 20 the die beds in order to maintain its proper relationship to the latter, is preferably secured to the journal box 4.

What I claim as my invention is:—

1. The combination of two rotary supporting means; coöperating die beds journaled one on each of the supporting means eccentric to the axis thereof; means for moving said beds into substantial parallelism when brought by the rotation of their supports into coöperative position; and telescopic alining means connected part with each die-bed adapted to engage to hold the die beds in accurate parallelism while they are in coöperative position.

2. The combination of two rotary supporting means; coöperating die beds journaled one on each of the supporting means eccentric to the axis thereof; means for moving said beds into substantial parallelism when brought by the rotation of their supports into coöperative position; telescopic alining means connected part with each die-bed adapted to engage to hold the die-beds in accurate parallelism while they 45 are in coöperative position; and means for varying the distance between the axes of the supporting means.

3. The combination of two rotary supporting means; coöperating die-beds journaled one on each of the supporting means eccentric to the axis thereof; means for moving said beds into substantial parallelism when brought by the rotation of their supports into coöperative position; alining means 50 connected part with each die-bed adapted to engage to hold the die-beds in accurate parallelism while they are in coöperative

position; chain conveying means extending between the die beds; and a projecting finger on one of the die-beds adapted to engage and move said conveying means.

4. The combination of two rotary supporting means; coöperating die-beds journaled one on each of the supporting means eccentric to the axis thereof; means for moving said beds into substantial parallelism when brought by the rotation of their supports into coöperative position; alining means connected part with each die-bed adapted to engage to hold the die-beds in accurate parallelism while they are in coöperative position; chain conveying means extending between the die-beds; a projecting finger on one of the die-beds adapted to engage and move said conveying means; and means for adjusting the finger to vary its extent of projection.

5. The combination of two rotary supporting means; coöperating die-beds journaled one on each of the supporting means eccentric to the axis thereof; means for moving said beds into substantial parallelism when brought by the rotation of their supports into coöperative position comprising a non-rotating cam for each support held in fixed relationship thereto and a crank arm on the die-bed engaging said cam; and telescopic alining means connected part with each die-bed adapted to engage to hold the die-beds in accurate parallelism while they are in coöperative position.

6. The combination of two rotary supporting means; coöperating die beds journaled one on each of the supporting means eccentric to the axis thereof; means for moving said beds into substantial parallelism when brought by the rotation of their supports into coöperative position comprising a non-rotating cam for each support held in fixed relationship thereto and a crank arm on the die-bed engaging said cam; telescopic alining means connected part with each die-bed adapted to engage to hold the die-beds in accurate parallelism while they are in coöperative position; and means for varying the distance between the axes of the supporting means.

Signed at Oshawa, Ont., this 11th day of November, 1915, in the presence of the two undersigned witnesses.

JOHN F. LAWSON.
